UNITED STATES PATENT OFFICE

99,932

DESIGN FOR A COMBINATION DESK UNIT

Fred H. Fisher, Syracuse, N. Y., assignor to Syracuse Ornamental Company, Syracuse, N. Y., a co-partnership composed of David M. Holstein, Alexander E. Holstein, Philip M. Holstein, and Moses Winkelstein

Application February 21, 1936, Serial No. 61,293

Term of patent 3½ years

To all whom it may concern:

Be it known that I, Fred H. Fisher, a citizen of the United States, residing at Syracuse, in the county of Onondaga and State of New York, and having my post-office address at 135 Sedgwick Road, Syracuse, New York, have invented a new, original, and ornamental Design for a Combination Desk Unit, of which the following is a specification, reference being had to the accompanying drawing, forming part thereof.

In the drawing;

The dotted line showing of the pen holder has been omitted from Figures 1 and 2 for convenience of illustration.

I claim:

The ornamental design for a combination desk unit, substantially as shown and described.

In testimony whereof, I have hereunto signed my name at Syracuse, in the county of Onondaga, and State of New York, this 17th day of February, 1936.

FRED H. FISHER.
